Samuel H. Ranson, Albany New York
Letters Patent (Design No. 141.) dated 7th August 1847

The schedule referred to in these Letters Patent and making
part of the same.

To all whom it may concern: Be it known that I Samuel H. Ranson of Albany in the County of Albany and State of New York have invented or produced a new ornamental design for a stone, and I do hereby declare that the accompanying drawings are full and accurate delineations thereof. Fig 1. is a perspective view of a stone constructed after my said design, Fig 2, an enlarged view of the side, in order to show the details of ornament, Fig 3 a view of one half, the front the other portion being of course symmetrical with this. The borders consist of a continuation of the figure c, d, d.

Fig 1. is a section of the moulding on over door and Fig 2 a section of that on the smaller door. Fig. 2, and the door in Fig. 3 both these doors being alike.

The whole though not easily described in words is fully represented in the accompanying drawings.

What I claim as my invention and desire to secure by letters patent is the combination and arrangement of ornamental figures herein represented, forming an ornamental design for a stone.
